AMBROSE POWELL, OF COXSACKIE, NEW YORK.

Letters Patent No. 68,578, dated September 3, 1867.

IMPROVED WASHING MACHINE.

The Schedule referred to in these Letters Patent and making part of the same.

TO ALL WHOM IT MAY CONCERN:

Be it known that I, AMBROSE POWELL, of Coxsackie, in the county of Greene, and State of New York, have invented a new and useful improvement in Washing Machines; and I do hereby declare the following to be a full and correct description of the same, sufficient to enable others skilled in the art to which my invention appertains to understand and use the same, reference being had to the accompanying drawings, which make part of the same, and in which—

Figure 1 is a plan of my improved machine.

Figure 2 is a section in line $x\ x$, fig. 1, and

Figure 3 is a detached view of the handle to operate the dasher.

Similar letters of reference indicate corresponding parts in the several figures.

The nature of my invention consists in a novel construction of a dasher, which forces the clothing against peculiarly shaped and arranged ribs on the sides of the machine, and in a novel arrangement of the handle to move said dasher.

A A' represents the box of my machine, the bottom B of which consists of three pieces, connected to each other at angles, or it may be made curved. Secured to the sides A of the box are ribs C, placed close to each other, as shown in the drawings. These ribs are flat on their rear or outer ends, and tapering off in curved lines towards their inner faces. Attached to the end pieces A', of the box are cleats D, which form bearings for the journals e of the dasher, which latter consists of the vertical piece e¹, the side pieces e² e³, and the horizontal pieces e³ and e⁴. The piece e¹ extends downward to the top of the piece e³. The pieces e² and e⁴ are triangular, their lower sides being slightly curved. The pieces e³ and e⁴ are straight on their top, and slightly on their under sides, the latter piece being wider than the former, and e³ wider than the pieces e² e³ together. The edges of these pieces are rounded off. In the dasher are two square holes f f, the piece e¹ being exected on each side to conform to the same. The holes receive the two arms g g of the handle G, which arms straddle the piece e¹.

The operation of my machine is as follows: Sufficient soap-suds being placed in the box, the dirty clothes are thrown in, and the handle being inserted into the holes f f, the dasher is operated by moving it forward and back. The clothes, saturated with suds, are pressed between the lateral pieces e², e³, and e⁴, and the vertical ribs C, and as they are pressed into the spaces between the pieces e², e³, and e⁴, and between the ribs C, the suds and water are pressed back through and out of the parts of clothes in those spaces, forcing the dirt out with them. By the continual repetition of this process, every part of the clothes is brought under its influence, and is rubbed, besides, by the dasher against the ribs and against the bottom of the box. If very fine washing is to be done, which will not bear great pressure, the handle G is removed and the dasher worked by means of the piece e¹. By removing the handle, after the washing is done, the machine can be stowed in a very small place.

Having thus described my invention, what I claim as new therein, and desire to secure by Letters Patent, is—

1. The combination of the vertical ribs C, and the dasher, constructed of the pieces e¹ e² e³ e⁴, substantially as described.
2. In combination with the above, the detachable handle G, constructed with forked end straddling the piece e¹ of the dasher, substantially as described.

The above specification of my improvement in washing machines signed this second day of April, 1867.

AMBROSE POWELL,
